UNITED STATES PATENT OFFICE.

JOSEPH J. BRIN, OF CHICAGO, ILLINOIS.

SYRINGE.

No. 805,339.

Specification of Letters Patent.

Patented Nov. 21, 1905.

Application filed July 20, 1905. Serial No. 270,513.

To all whom it may concern:

Be it known that I, JOSEPH J. BRIN, a citizen of the United States, residing at Chicago, in the county of Cook, State of Illinois, have 5 invented certain new and useful Improvements in Syringes, of which the following is a specification.

My invention relates to that class of syringes wherein there is used an expanding and contracting frame whereby the walls of the vagina or other parts may be dilated to facilitate the treatment thereof; and my invention consists, chiefly, in the novel means and manner of expanding and contracting said frame. 10 There are certain well-known objections to syringes of this type, such as the pinching of the tissue membrane or the like when the frame is contracted and the difficulty of operating the same without disturbing the position of the syringe when once set. In my invention I avoid these inconveniences and provide a syringe of simple, economical, and durable construction by which there can be no pinching or tearing of the tissues, and means 15 are provided for adjusting the same without disturbing its position.

To these ends my invention consists, chiefly, in the provision of an expanding device of novel form in combination with any suitable 20 form of bulb member to coöperate therewith.

In the drawings, Figure 1 is a side elevation with parts broken away and other parts in section. Fig. 2 is a detail view of the cone. Fig. 3 is an elevation, partly in section, of a 25 modified form of my invention. Fig. 4 is a detail view of the cap for the cone. Fig. 5 is a detail plan view of the cone with the cap removed, and Fig. 6 is a cross-sectional view on line 6 6 of Fig. 2.

Referring to the drawings, 1 represents a bulb of any desired form having a cap or collar 2, connected to a discharge-pipe or spray-tube 3 in any desired manner, two methods being shown at 4 and 5.

6 is a sliding tube fitting over the discharge-pipe and carrying an air-cushion member 7, having apertures 8 for the purpose of the ingress and egress of air and supported at its base by the plate 9, which in turn is supported 45 by the ring 10, secured to the sliding tube by means of the screw 11, the top portion of said cushion member fitting closely around the upper end of the sliding tube, as shown at 12. To the sliding tube there is attached the cone 50 13 or other suitable head by means of the rod 14, secured to the sliding tube and cone by

any suitable means, as shown at 15 and 16. 17 is a cap secured to the end of the cone by means of the screw 18. The walls of the cone are preferably, and as herein shown, inwardly 60 convergent, providing surfaces of different angles and said surfaces having connecting-slots 21 and 22 therein.

23 represents fingers constituting an expanding frame or dilator, which fingers are of any 65 desired form, preferably flat on their upper faces and secured to the discharge-pipe or spray-tube, as shown at 24, and carrying lugs 25 and 26, adapted to fit within and without said cone, said lugs traveling on either side of 70 the slots to securely retain the fingers therein, the outside lugs being beveled at 27 and at substantially the same angle as the beveled surface 20. In the preferred mode of operation one hand of the operator engages the 75 cushion 7 while the other engages the bulb member 1. Then by a forward movement of the bulb member the spray-tube and dilator are advanced, forcing the lugs to move up the inclined surfaces of the cone in the slots or 80 tracks and distending the fingers. In contracting my device the operation is reversed and the fingers in their downward and inward course move constantly away from the tissue down the slots of the cone until the lowest point 85 of the bevel is reached when the contraction becomes complete. It is evident that by the downward and inward movement of said finger-dilators the tissue slides free from the fingers and cone, as they lie practically in the 90 same plane when the fingers are in a contracted position, thus rendering the pinching or lacerating of the tissues impossible.

A feature not heretofore explained, but which is regarded as important, is that the 95 finger members project beyond the end of the cone, thus allowing a free flow of liquid around the end of the cone. It is also to be noted that as the bearing-surfaces of the lugs (shown at 27) are on the same angle as the 100 surface 20 of the cone the finger members do not collapse under external pressure, and that when the lugs have passed the surface 19 such external pressure will collapse the fingers, permitting the ready withdrawal of the 105 instrument. It will also be seen that the cone-shaped head serves the function of a guard to prevent the tissue or membrane from becoming pinched or lacerated between the fingers in the contracting movement of the latter, since it serves to hold the membrane or 110 tissue away from the fingers during the con-

tracting movement. It will also be observed that the fingers are expanded by and during the act or movement of applying the instrument and, conversely, are retracted by the act 5 or movement of withdrawing the same, thus accomplishing the double function by a single movement of the instrument.

It is obvious that various changes in my invention may be made without departing from 10 the spirit of the same, such as converting it into a fountain-syringe by attaching to the spray-tube a hose having a suitable bulb attachment and providing the spray-tube with a disk having radially-disposed apertures, as 15 shown at 28, to produce a spray in place of a solid stream, or the bar 14 may be in the form of a tube having apertures connected to a perforated cone.

Having fully described my invention, what 20 I claim, and desire to secure by Letters Patent, is—

1. In a syringe the combination with a spray-tube of a series of distending-fingers surrounding said tube and means for distending said 25 fingers comprising a head to which the outer ends of said fingers are slidably connected and means for imparting a relative sliding movement to said cone and finger members, substantially as described.

2. In a syringe the combination with a spray-tube, of a series of distending-fingers surrounding said spray-tube, a beveled head to which the outer ends of said fingers are slidably connected and means for imparting a relative 35 sliding movement to said head and finger members, substantially as described.

3. In a syringe the combination with a spray-tube, of an expandible frame, a beveled head having tracks within it, the frame being slidably 40 connected to said tracks whereby the ends of the frame will lie concealed within said head when in a contracted position, and means for imparting a relative sliding movement to said head and frame, substantially as described.

4. In a syringe the combination with a spray-tube having fingers attached thereto, of a sleeve sliding upon said tube, a beveled cone attached to said sleeve, grooves within said cone to which the fingers are slidably connected, and

means for imparting a relative sliding movement to said cone and finger members, substantially as described. 50

5. In a syringe the combination with a spray-tube of a series of distending-fingers, a sleeve sliding upon said spray-tube and provided with a cushion, a slotted cone attached to said sleeve, to which the outer ends of said fingers are slidably connected and means for imparting a relative sliding movement to said cone and finger members, substantially as described. 55

6. In a syringe the combination with a spray-tube, of a series of distending-fingers surrounding said tube, means for distending said fingers comprising a cone to which the outer ends of said fingers are slidably attached and project beyond the end of the cone, and means for imparting a relative movement to said cone and finger members, substantially as described. 60

7. In a syringe, the combination with a spray-tube, of a series of distending-fingers surrounding said tube, and means for distending said fingers comprising a head to which the outer ends of said fingers are slidably connected, said head being of a form and size to serve as a guard for the ends of said fingers, and means 70 for imparting a relative sliding movement to said head and fingers, substantially as described.

8. In a syringe, the combination with a spray-tube, of a series of distending-fingers surrounding said tube, means for expanding and contracting said fingers comprising a longitudinally-grooved cone-shaped head to which the outer ends of said fingers are slidably attached, the grooved guides of said head being inwardly 85 convergent at a greater angle throughout their inner portions than throughout their outer portions whereby said fingers resist compression through external contraction throughout the first part of their contracting 90 movement and yield to external compression throughout the latter part of their contracting movement, substantially as described.

JOSEPH J. BRIN.
